UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed April 6, 1922. Serial No. 550,022.

To all whom it may concern:

Be it known that I, LIONEL M. WOOLSON, a citizen of the United States, and resident of Detroit, Wayne County, State of Michigan, have invented certain new and useful 5 Improvements in Internal-Combustion Engines, of which the following is a specification.

This invention relates to internal combustion engines and particularly to means for 10 forming a heated combustible mixture for the engine.

In the building of combustion heaters for 15 internal combustion engines it has been found that in nearly every case there are special problems which have to be worked out in order to produce satisfactory results. It has been found that a combustion heater device that is satisfactory for one engine or 20 for one carburetor is not at all practicable for a slightly different engine or carburetor. In some cases it is found desirable to provide a special carburetor or mixing device for obtaining the mixture for the combustion 25 heater and in other cases one form of means for withdrawing the mixture from the carburetor or intake conduit of the engine is satisfactory under some conditions and impracticable under others.

30 The theory of the type of combustion heater, which is arranged in parallel with the engine intake header and which operates by the suction in said header above the throttle valve of the engine, is that the heater will be operated at its maximum on 35 low throttle and at its minimum or not at all on wide open throttle. Somewhere between those two extremes the action of the heater becomes negligible, and individual 40 users differ as to the desirable point at which the heater should "go out" or become inactive. For instance, some users feel that it is not necessary for the heater to operate above fifteen or twenty miles per hour 45 in an automobile in which the engine and heater are used, while others want the heater to remain active up to thirty or forty miles per hour.

Carburetors, and the theories upon which 50 carburetors are built, also differ greatly amongst the different users and engineers and manufacturers, but this applicant has found by exhaustive experiments that a

somewhat leaner mixture may be used at the lower suction or the lower speeds or 55 loads than is required for the intermediate speeds or the full loads. Again, at the much higher speeds a somewhat thinner mixture may be used due probably to the exceptional turbulence that is set up in the 60 engine cylinders at those speeds.

As the result of the above referred to experiments this applicant has produced a carburetor in which a mixture having a certain degree of richness is produced for the lower 65 speeds of the engine or the lower suction, and a richer mixture is obtained when a greater load is required or when the increased suction of the motor is calling for it.

In attempting to combine previous combustion heaters with this new carburetor a distinct difficulty arose. It was found that when just the right mixture was withdrawn from the carburetor or intake header for operating the combustion heater at the 75 lower speeds, the mixture withdrawn at the higher or intermediate speeds of the engine would be found to be so rich that the heater would "go out" or cease to function. Then it was found that by bleeding air into the 80 withdrawn mixture on its way from the carburetor to the combustion heater the mixture would be thinned out sufficiently for operating the heater at the higher speeds 85 where it would be too thin for the lower speeds where the heater is really of the greatest benefit.

The object of the experiments then became to find a way to thin the withdrawn mixture at the higher speeds while at the 90 same time maintaining the correct proportions of it at the lower speeds, when the mixture is withdrawn from a carburetor of the type hereinabove described, and without, of course, the added complication of 95 movable valves and mechanical moving parts.

It was found that by bleeding air into the lower part of the heater combustion chamber, that is, beneath the mixture inlet and 100 the igniter, a wide range of degrees of richness of the mixture in the combustion chamber was found to exist, and by reason of the steady burning of the mixture brought about by the rapid moving of it through 105 the combustion chamber and the agitation

of it just prior to its reaching the spark plug, the heater would remain active throughout a much longer range of speed and could even be kept to considerable heating capacity up to as high as fifty miles per hour.

It was further found that by adjusting this air bleed in the lower part of the combustion chamber, the point at which the heater would "go out" could be changed at will, within reasonable limits of course, and this made the heater most admirably adjustable to the different ideas of various users.

15 Therefore, one of the objects of this invention is to provide a carburetor of the above referred to type with a heater means of the combustion type that will operate over a wide range of speeds of the engine.

20 Another object of the invention is to provide a combustion heater which is readily adjustable to cutting out at various speeds without the use of mechanical moving parts.

Other objects of the invention will appear 25 from the following description taken in connection with the drawings, which form a part of this specification, and in which the figure is a vertical section through an internal combustion engine intake conduit, a carburetor attached thereto, and a combustion heater combined with the carburetor and intake conduit, all built in accordance with this invention.

Referring to the drawings 10 represents 30 a cylinder block of an internal combustion engine and 11 is the intake header or conduit of the engine, being detachably connected thereto as by bolts 12. The intake header is in the form of an elbow and its downwardly 35 extending end is formed to receive a carburetor 13 so that the discharge end 14 of the carburetor registers with the inlet end 15 of the intake conduit. The upper part of the carburetor, therefore, becomes a continuation 40 of the intake conduit and at a suitable point therein the motor throttle valve 16 is arranged. It is shown as mounted in the upper part of the carburetor body and it is adapted to be operated in the usual way to 45 regulate the quantity of mixture passing to the motor.

The part of the carburetor just below the throttle valve 16 may be termed the mixing chamber 17, and the other main parts of the 50 carburetor are a float chamber 18, a fuel nozzle 19 communicating with the float chamber, a main air intake 20, an auxiliary air intake 21 controlled by the spring pressed valve 21', and a mixing tube 22. A float 55 23 in the float chamber operates a valve 24 which controls the inlet port 25 in the usual way to maintain the liquid fuel in the float chamber at the required level. A supply pipe 26 communicates with the port 25 to 60 supply the fuel.

The mixing tube 22 is mounted in the lower part of the mixing chamber 17 and it is shown as of Venturi form. Its lower end communicates with the main air intake passage 20. Thus the air entering the carburetor through the main air intake pipe upwardly through the mixing tube 22, and the air from the auxiliary air intake 21 passes upwardly around the outside of the mixing tube 22 into the mixing chamber 17. 70

The nozzle 19 is preferably formed of two tubes 27 and 28, as shown, and a plug 29 by which it is secured in place. The outer tube 27 is secured in the plug 29 and the inner tube 28 extends into the outer tube. The upper end 30 of the outer tube is separated 80 from the exterior of the inner tube to form a well 31 and the upper end of this well is so located relative to the mixing tube 22 and the float chamber 18 that it is approximately 85 at the neck of the Venturi tube and slightly above the level of the fuel in the float chamber. A restricted port or orifice 32 in the inner tube determines the amount of fuel that may be fed to the well 31. 90

This well 31, formed as shown, has several advantages; first because of its free open end and its restricted inlet orifice 32 it will feed liquid fuel to the venturi at the correct ratio for idling and relatively low suction without danger of leakage when the motor stops, and second when the motor is started the well will supply a rich mixture momentarily but without a continuation of it that is likely to choke the engine. For the higher suction 100 when the maximum power of the motor is required the nozzle is provided with an extension outlet 33 which passes upwardly above the well 31 to the upper part of the mixing tube 22, its end 34 discharging directly into the mixing chamber. Throughout the length of this extension the interior is considerably restricted so that it will act frictionally on the liquid passing through it and thus retard its passage to some extent. 105

From the above description of the construction of the fuel nozzle it will be seen that the well 31 will be nearly full of fuel when the engine is not running and as soon as the engine is turned over, thus creating 110 suction in the intake pipe 11, this liquid fuel will be drawn into the mixing tube 22 and the mixing chamber 17 with the incoming air and a rich mixture will be formed for starting. As soon as the well 31 has been 115 emptied the small port 32 will determine the amount of gasoline fed to the mixing tube and this is sufficient for idling and for the lower range of operating speeds, or low suction. When the throttle valve is opened 120 wider and a greater suction prevails, however, the liquid fuel will be drawn up farther in the nozzle and will discharge from the outlet 34 directly into the mixing chamber 17. This additional supply of liquid 125 130

fuel will compensate for the additional air that is drawn in through the intake 21 by reason of the larger suction, and the mixture will be properly proportioned for the heavier duty required. The fuel is retarded by friction as it passes through the extension 33 sufficiently to prevent an over rich mixture at very high suction.

The heater part of this invention comprises a combustion chamber 35 which may be formed as an integral jacket on the intake conduit 11 so that a wall 36 between the interior of the intake conduit and the combustion chamber 35 may constitute a heat transferring wall through which the heat in the combustion chamber may pass to the mixture in the intake conduit.

There is an upward extension 37 of the combustion chamber 35 whereby the chamber is somewhat elongated and a passage 38 leads to an outlet port 39 communicating with the interior of the intake conduit above the throttle valve 16. This port 39 is considerably larger than the mixture inlet to the combustion heater which inlet will be hereinafter described and by the arrangement shown it will be seen that the combustion chamber is always under the influence of the suction in the intake conduit above the throttle valve.

The extension 37 of the combustion chamber is formed in a casting 40 which is detachably secured to the main body of the heater as by a pair of bolts 41 and to the upper part of the casting 40 is connected a pipe or conduit 42 as by an elbow 43. A nut 44 holds the elbow in place and a screen 45 is clamped between the inner end of the nut 44 and a shoulder 46. A spark plug 47 or other form of igniter, is arranged in the upper end of the extension 37 of the combustion chamber, near the inlet or feeding means from the pipe or conduit 42. The size of the passage or conduit for the mixture is determined by the drilled opening 48 in the elbow 43 and it will be seen that this is much smaller than the outlet 39 above described.

The other end of the pipe 42 is connected to a hollow shaft 49 upon which the throttle valve 16 is mounted and the interior of the pipe 42 communicates with the interior of said shaft 49. The shaft 49 also has one or a series of radial openings 50 which are extended through the throttle valve 16 to the under side of said valve, so that when the valve is closed, as shown in the drawing, the openings or ports 50 will communicate with the mixing chamber 17 below the throttle valve.

Communicating with the lower part of the combustion chamber 35 and particularly between the igniter 47 and the outlet port 39, is an air inlet means comprising a passage 51 and a valve plug 52. The plug 52 has side ports 53 and a needle valve 54 controls

the size of the passage through the plug so that the amount of air admitted to the combustion chamber may be regulated. The valve may be locked in position by a nut 55.

In operation, at the lower range of suction, most of the air for the carburetor will be drawn through the main intake 20 and the liquid fuel will be drawn from the well 31 and through the small orifice 32, the air valve 21' being seated throughout the greater part of this range of action. The suction will not be strong enough to draw the liquid fuel up to the top of the inner tube 33 of the nozzle. The resulting mixture will be right for the small amount of power that is required from the engine and part of the mixture will be withdrawn from the mixing chamber 17 through the pipe 42 and discharged through the screen 45 into the combustion chamber 35. Air will also be drawn through the air plug 52 into the lower part of the combustion chamber 35, but this air will not materially affect the mixture in the vicinity of the spark plug 47. The spark plug or igniter will therefore readily ignite the mixture and the products of combustion will pass through the port 39 into the intake conduit where it will be combined with the mixture passing to the engine and will heat that mixture so that it will be readily ignited in the engine cylinders.

As the throttle is opened or as the speed of the motor increases a greater suction is produced on the fuel nozzle so that liquid fuel is drawn from the upper end 34 of the nozzle and at the same time the greater suction also opens the valve 21'. The proportions of these are such that a somewhat richer mixture is produced for the required increase of power and some of this richer mixture is of course withdrawn by the connections to the pipe 42 and is discharged into the upper end of the combustion chamber 35. The mixture in the combustion chamber is burning steadily and the igniter 47 could even be cut out of action without affecting the result. The spark is maintained, however, for re-lighting the heater in case the flame becomes extinguished for any reason. But with this steadily burning mixture and the increased richness of it due to the difference in the action of the carburetor, the flame in the combustion chamber moves downwardly below the spark plug 47 and to the lower part of the chamber because somewhere between the spark plug and the chamber outlet the mixture is at just the right proportion for complete combustion, due, of course, to the air which is admitted to the chamber between the spark plug and the chamber outlet.

By adjusting the size of the opening through the air plug 52 the flame will be seen to rise or drop in the combustion chamber, and as the speed of the engine is

increased or the throttle opening changed the same rise or fall will occur. Eventually, as by closing off the air inlet entirely or by opening up the throttle very wide, the flame may go out entirely due to the resulting changes in the mixture.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the spirit or 15 scope of my invention.

Having thus described my invention, what I claim and desire to secure by Letters Patent is:

1. In an internal combustion engine, the 20 combination with a carburetor adapted to deliver a lean mixture over a low speed range and a richer mixture over a higher speed range, of a combustion heater comprising a combustion chamber connected to the 25 engine suction between the throttle valve and the engine cylinder, a conduit arranged to withdraw a portion of the mixture formed by the carburetor and feeding it downwardly into the top of said chamber, an igniter for 30 the mixture arranged adjacent to the point of feeding-in, and air inlet means for the chamber below the igniter.

2. In an internal combustion engine, the 35 combination with a carburetor adapted to deliver a lean mixture over a low speed range and a richer mixture over a higher speed range, of a combustion heater comprising a combustion chamber connected to the engine suction between the throttle valve and the 40 engine cylinder, a conduit arranged to withdraw a portion of the mixture formed by the carburetor and feeding it downwardly into the top of said chamber, an igniter for the mixture arranged adjacent to the point 45 of feeding-in, and air inlet means for the chamber between the igniter and the suction connection.

3. In an internal combustion engine, the 50 combination with a carburetor adapted to deliver a lean mixture over a low speed range and a richer mixture over a higher speed range, of a combustion heater comprising a combustion chamber connected to the engine suction between the throttle valve and 55 the engine cylinder, a conduit arranged to withdraw a portion of the mixture formed by the carburetor and feeding it downwardly into the top of said chamber, an igniter for the mixture arranged adjacent to the point 60 of feeding-in, and air inlet means at the lower part of the chamber.

4. A combustion heater comprising a 65 chamber, a mixture inlet means at the upper part of the chamber, outlet means at the lower part of the chamber, an air inlet means

at the lower part of the chamber, and an igniter arranged near the inlet means.

5. A combustion heater comprising a chamber, a mixture inlet means at the upper part of the chamber, outlet means at the lower part of the chamber, an adjustable air inlet means at the lower part of the chamber, and an igniter arranged near the inlet means.

6. A combustion heater comprising a 70 chamber having mixture inlet means at its upper part, an outlet means of greater capacity than the inlet means and arranged in the lower part of the chamber, an igniter arranged in the chamber near the inlet 80 means, and an air inlet means adapted to admit air to the chamber between the igniter and the outlet means.

7. In an internal combustion engine, the 85 combination with a carburetor adapted to deliver a lean mixture over a low speed range and a richer mixture over a higher speed range, of a combustion heater comprising a combustion chamber connected to the engine suction between the throttle valve 90 and the engine cylinder, a conduit arranged to withdraw a portion of the mixture formed by the carburetor and feeding it to said chamber, means comprising an air inlet for said chamber, and means for igniting the 95 mixture in the chamber.

8. In an internal combustion engine, the 100 combination with a carburetor adapted to deliver a lean mixture over a low speed range and a richer mixture over a higher speed range, of a combustion heater comprising a combustion chamber connected to the engine suction between the throttle valve 105 and the engine cylinder, a conduit arranged to withdraw a portion of the mixture formed by the carburetor and feeding it to said chamber, means comprising an air inlet for the chamber remote from the point where the mixture is fed to the chamber, and means for igniting the mixture in the chamber. 110

9. In an internal combustion engine, the 115 combination with a carburetor adapted to deliver a lean mixture over a low speed range and a richer mixture over a higher speed range, of a combustion heater comprising a combustion chamber connected to the engine suction between the throttle valve and the engine cylinder, a conduit arranged to withdraw a portion of the mixture formed by the carburetor and feeding it to said chamber, 120 means comprising an air inlet for the chamber remote from the point where the mixture is fed to the chamber, and an igniter for the mixture arranged between the feeding-in point and the air inlet. 125

10. Means for forming a heated combustible mixture for internal combustion engines, comprising, in combination, a carburetor adapted to deliver a lean mixture on low suction and a richer mixture on higher suc- 130

tion, a combustion chamber independent of the combustion space in the engine, a conduit connected to withdraw part of the mixture delivered by the carburetor, means for feeding the withdrawn mixture into the upper part of said chamber, means comprising

10 withdrawing the products of combustion from the combustion chamber, means for feeding air into the lower part of the combustion chamber, and an igniter in the combustion chamber.

In testimony whereof I affix my signature.

LIONEL M. WOOLSON.
